COMBINED HAND TRUCK AND LADDER

Perry H. Hoey, Silver Spring, Md.

Application April 20, 1950, Serial No. 9,346

Term of patent 7 years

(Cl. D14—3)

To all whom it may concern:

Be it known that I, Perry H. Hoey, a citizen of the United States, residing at 9115 Eton Road, Silver Spring, in the county of Montgomery and State of Maryland, have invented a new, original, and ornamental Design for a Combined Hand Truck and Ladder, of which the following is a specification, reference being had to the accompanying drawings, forming a part thereof.

The figure is a perspective view of a combined hand truck and ladder, showing my new design.

The essential features of my design reside in the portions shown in full lines.

I claim:

The ornamental design for a combined hand truck and ladder, as shown and described.

PERRY H. HOEY.
